UNITED STATES PATENT OFFICE.

HENRY K. DYER, OF BROOKLYN, ASSIGNOR TO THE DENNISON MANUFACTURING COMPANY, OF NEW YORK, N. Y.

EXHIBITION-TRAY.

SPECIFICATION forming part of Letters Patent No. 430,842, dated June 24, 1890.

Application filed March 10, 1890. Serial No. 343,339. (No model.)

To all whom it may concern:

Be it known that I, HENRY K. DYER, of the city of Brooklyn, Kings county, and State of New York, have invented a new and Improved Exhibition-Tray, of which the following is a full, clear, and exact description.

The object of my invention is to provide a cheap and attractive exhibition-tray, designed more particularly for jewelers' use, and so constructed that the covering of the central portion on which the articles are placed may be readily changed so that a variety of covers may be used with the same frame-work.

Reference is to be had to the accompanying drawings, forming a part of this specification, in which similar letters of reference indicate corresponding parts in all the figures.

Figure 1 is a perspective view of my new exhibition-tray made in circular form, and covered in the center with cotton. Fig. 2 is a sectional elevation of the same. Figs. 3 and 4 show modified forms of the tray.

The tray comprises the center-piece A and the border B, and removable covering C, held between the center-piece and border. The outline of the tray may be of any desired design, as circular, square, or triangular, or in the form of a cross, as in Fig. 3, or a scroll, as in Fig. 4. The center-piece is sawed out, 30 leaving the border which it fits. The border

is then polished, or it may have a fancy covering D, of felt or other material. The tray may be provided at the back with a hinged support or leg E, by which the tray may be held in inclined position, or by folding the leg flat against the bottom of the tray it may be placed in a flat position in a show-case or window. The center-piece A is held in place by pressure, and to change the cover C, which may be of silk, velvet, cotton, wool, or any other suitable material, it is only necessary to press out the center-piece, place the cover over it, and press it back to place again, binding the edges of the cover between it and the border.

Having thus described my invention, what I claim as new, and desire to secure by Letters Patent, is—

As a new article of manufacture, an exhibition-tray comprising a narrow border covered with plush or other fabric, combined with a removable center-piece held within and by the border, and a cover for the center-piece held between the outer edge of the center-piece and the adjacent edge of the border, substantially as described.

HENRY K. DYER.
